UNITED STATES PATENT OFFICE.

EDWARD WILLIAM BARRATT, OF WOOD GREEN, ENGLAND.

MANUFACTURE OF SWEETMEATS OR SIMILAR ARTICLES OF CONFECTIONERY.

SPECIFICATION forming part of Letters Patent No. 743,219, dated November 3, 1903.

Application filed July 8, 1903. Serial No. 164,635. (No specimens.)

To all whom it may concern.

Be it known that I, EDWARD WILLIAM BARRATT, manufacturer, a subject of the King of Great Britain, residing at 1 Tower Terrace, 5 Wood Green, in the county of Middlesex, England, have invented certain new and useful Improvements Relating to the Manufacture of Sweetmeats or Similar Articles of Confectionery, of which the following is a specification.

This invention relates to the manufacture of sweetmeats and similar articles of confectionery, and has particular reference to the operation known as "pulling" sugar or candy.

The chief object of the present invention 15 is to devise a simple and comparatively inexpensive machine for effecting this operation. I provide two rigid bars, which I term "stationary" pulling-bars, and a movable bar, which I term a "traveling" pulling-bar.

This traveling pulling-bar is by the action of 20 two pairs of rotary arms caused to revolve about the stationary pulling-bars in a course somewhat resembling the figure 8 lying on one of its sides, this result being attained according to my present invention by arranging 25 the rotary arms of each pair on opposite sides of the machine, so that each pair can support opposite ends of the traveling pulling-bar. The said two pairs of rotary arms are

30 caused to revolve about their axes, and their ends describe circular paths around the stationary pulling-bars, which are held rigidly in place by fixed arms arranged opposite one another in pairs, the paths of the said ends 35 of the rotary arms closely approaching or touching one another once during each of their revolutions at a point approximately diametrically opposite the axis of each of the stationary pulling-bars. The revolutions of

40 the rotary arms are in opposite directions, and the speed of revolution varies, so that each time one pair of the said arms passes the other pair the traveling pulling-bar will be caught by the pair of rotary arms of greater 45 speed and transferred thereto from the other pair, suitable means, such as a catch arrangement, being provided for retaining the traveling pulling-bar in the pair of arms which for the time being carry it and for liberating 50 it when the time arrives for it to be transferred to the other pair of arms.

In the accompanying drawings, Figure 1 is

a side elevation of the sugar-pulling machine; Fig. 2 is an end elevation, and Fig. 3 a plan, of the same. Fig. 4 is a detail sectional view, 55 on an enlarged scale, showing the catch arrangement for locking and unlocking the traveling pulling-bar to and from the rotary arms.

A is the base of the machine, carrying upwardly-projecting standards or supports A' A' A² A², arranged in pairs on opposite sides of the machine. These standards are provided at their upper ends with short inwardly-projecting stationary axles a' a' a² a², furnished with rotary sleeves having radial arms a³ a³ a⁴ a⁴. The radial arms have recessed extremities for the reception of the ends of the traveling pulling-bar B. Each radial arm is furnished with the aforesaid catch arrangement, which in the example illustrated comprises a sliding plate or finger a, Fig. 4, having guide-slots a⁵ a⁵, through which pass screws a⁶ for retaining said finger in place and permitting it to slide. The inner end of 70 the finger is connected by a link a⁸ with a lever a⁷, transversely mounted on the rotary arm. The free end of this lever a⁷ is by the action of a spring a⁸ pressed against a cam a⁹, fixed on each of the stationary axles a' a², 75 so that as the rotary radial arms revolve the said cam will cause the finger a to slide to and fro over the entrance to the recessed end of the said radial arms, so as to open and close the same. The shape of the said cams is such 80 that the said fingers are kept in their closing position until the ends of the pairs of radial arms approach each other in their revolution, when said fingers are withdrawn to uncover the recessed ends and permit the transference of the traveling pulling-bar from one 85 pair of radial arms to the other, which operation occurs as said ends pass each other. In order to enable this transference to take place, the outer or recessed ends of one pair 90 of the radial arms must pass the outer or recessed ends of the other pair. The outer ends of the pair of radial arms a³ are therefore bent or otherwise formed in such manner as to move in a different plane to that of the other pair a⁴, as shown in Figs. 2 and 3. The said radial arms a³ a⁴ are adapted to travel at different speeds as they pass each other, so as 95 to enable the one of greater speed to overtake 100

the other and in so doing to remove the traveling pulling-bar B therefrom. For this purpose the sleeves carrying the radial arms are furnished with pulleys or sprocket-wheels a^{10} , which by means of endless bands or chains a^{11} are geared with pulleys or sprocket-wheels a^{12} , mounted on transverse shafts a^{13} a^{18} , situated below the base of the machine, the said pulleys or sprocket-wheels a^{12} being 10 twice the diameter of the pulleys or sprocket-wheels a^{10} , and therefore imparting thereto and to the rotary arms twice the number of revolutions of the pulleys or sprocket-wheels a^{12} . The shafts a^{13} are geared together 15 by a pair of toothed wheels a^{14} a^{14} , which are eccentrically mounted on their shafts, as shown in Fig. 1. One of the said shafts also carries a toothed wheel a^{15} , Fig. 2, to which motion is imparted from the main driving 20 shaft a^{17} by a toothed pinion a^{16} , this main shaft being also situated beneath the base of the machine. By means of the above-described gearing a^{10} a^{11} a^{12} rotary motion is imparted to the pairs of radial arms in opposite directions, as represented by the arrows 25 in Fig. 1, and an unequal speed is imparted to the shafts a^{13} a^{18} , and therefore to the arms, by the eccentric gear-wheels a^{14} a^{14} , the greatest difference in the speed of the radial 30 arms taking place when the ends of one pair pass those of the other pair.

C are the stationary pulling-bars, which are fixed in arms c' c^2 , forming part of the fixed axles a' a^2 , said arms projecting horizontally from the axles in opposite directions, as represented in Figs. 1 and 3. The length of these arms is such that the stationary pulling-bars lie within the circular path described by the ends of the radial arms a^3 a^4 , so that 35 as said radial arms revolve and alternately carry the traveling pulling-bar from one to another, as above explained, the pulling of the sugar or candy will be effected, as is well understood in connection with sugar-pulling 40 machines. The aforesaid traveling pulling-bar has adjustable collars b b' , which operate to keep the sugar or candy from extending beyond the ends of said pulling-bar during the working of the machine. These collars 45 can be set closer to or farther from each other, in accordance with the quantity of sugar or candy to be treated in the machine. Near the ends of the said traveling pulling-bar are enlargements or bosses b' b' , which serve as 50 guides for keeping the said pulling-bar from undue longitudinal movement in the recessed ends of the rotary arms a^3 a^4 .

In order to avoid the too-rapid cooling of the sugar or candy during the pulling operation, I 55 may supply steam or other hot fluid to the stationary pulling-bars C, which are then made hollow and connected by means of passages c^3 c^3 , Fig. 4, in the arms c^2 and the axles a^2 with pipes c^4 c^4 . The said hot fluid would 60 pass in and through one of the stationary pulling-bars and then pass (by a connecting-pipe) across to and through the other stationary

pulling-bar, whence it would pass back to the source of supply. A constant circulation of the hot fluid would in that way be provided. 70

If desired, a removable tray may be provided on the bed of the machine, so that in the event of the sugar or candy dropping from the pulling-bars during the working of the machine it will fall onto said tray, which can 75 be readily withdrawn with the sugar or candy and the latter be picked up by the machine attendant for replacing onto the pulling-bars without the attendant subjecting himself to danger of being injured by the machine. 80

I wish it to be understood that I do not limit myself to the specific means hereinbefore described for locking and unlocking the traveling pulling-bar to and from the radial arms a^3 a^4 , as any other suitable means may be 85 employed for this purpose.

I claim—

1. In a sugar or candy pulling machine, the combination of two stationary pulling-bars, a traveling pulling-bar, two pairs of rotary arms having their outer ends adapted to receive said traveling pulling-bar; means for causing said rotary arms to revolve at unequal speeds in opposite directions about the said stationary pulling-bars and to pass each other 90 during their revolution in order to transfer said traveling pulling-bar from one pair of arms to the other and means for causing said traveling pulling-bar to be locked and unlocked to and from said rotary arms at the 95 proper times, for the purpose specified.

2. In a sugar or candy pulling machine, the combination of two stationary pulling-bars, a traveling pulling-bar, two pairs of rotary arms having recessed outer ends for receiving 100 said traveling pulling-bar, means for causing said rotary arms to revolve at unequal speeds in opposite directions about the said stationary pulling-bars and to pass each other during 105 their revolution in order to transfer said traveling pulling-bar from one pair of arms to the other, a sliding piece near the outer end of each of said rotary arms and means for causing said sliding piece to advance and retire for opening and closing said recessed ends, 110 substantially as and for the purpose specified. 115

3. In a sugar or candy pulling machine, the combination of two stationary pulling-bars, a traveling pulling-bar, two pairs of rotary arms having recessed outer ends for receiving 120 said traveling pulling-bar, means for causing said rotary arms to revolve at unequal speeds in opposite directions about the said stationary pulling-bars and to pass each other during 125 their revolution, in order to transfer said traveling pulling-bar from one pair of arms to the other, a sliding piece near the outer end of each of said rotary arms, a spring-controlled lever carried by each of said rotary arms and connected with said sliding piece, and a fixed 130 cam against which said lever bears during the revolution of the rotary arms, substantially as and for the purpose specified.

4. In a sugar or candy pulling machine, the

combination of two stationary pulling-bars, a traveling pulling-bar, two pairs of rotary arms having their outer ends adapted to receive said traveling pulling-bar, sleeves on 5 said rotary arms, fixed axles upon which said sleeves are rotatably mounted, wheels fixed to said sleeves, means for revolving said wheels at unequal speeds in opposite directions to enable the traveling pulling-bar to be transferred from one pair of rotary arms to the other as said arms pass one another, and means for causing said traveling pulling-bar to be locked to and unlocked from said rotary arms at the proper times substantially as and 10 for the purpose specified.

5. In a sugar or candy pulling machine, the combination of two stationary pulling-bars, a traveling pulling-bar, two pairs of rotary arms having their outer ends adapted to receive 15 said traveling pulling-bar, means for causing said traveling pulling-bar to be locked

to and unlocked from said rotary arms at the proper times, sleeves on said rotary arms, fixed axles upon which said sleeves are rotatably mounted, arms projecting from said sleeves to carry the stationary pulling-bars, sprocket-wheels fixed to said sleeves, sprocket-wheels mounted on shafts beneath the bed-plate of the machine and adapted to drive the sprocket-wheels of the sleeves at a speed twice that of their own speed, toothed wheels eccentrically mounted on the said shafts and gearing with each other, and means for driving one of said shafts substantially as and for the purpose specified.

In testimony whereof I have hereunto set my hand, in presence of two subscribing witnesses, this 24th day of June, 1903.

EDWARD WILLIAM BARRATT.
